UNITED STATES PATENT OFFICE

THEODORE WILLARD CASE, OF AUBURN, NEW YORK, ASSIGNOR TO CASE RESEARCH LABORATORY INCORPORATED, OF AUBURN, NEW YORK, A CORPORATION OF NEW YORK

INDUCTIVE LIGHT SOURCE

Application filed July 23, 1928. Serial No. 294,867.

This invention relates to a certain new and useful inductive light source.

The main object of the invention is to produce a novel, attractive and intense source 5 of light which may be maintained at an effective constant intensity or varied in accordance with sound waves for television, light telephony, light signaling, etc.

Other objects and advantages relate to the 10 details of the device and the relation of the parts thereof, all as will more fully appear from the following description taken in connection with the accompanying drawings, in which:—

15 Figure 1 diagrammatically illustrates an embodiment of the invention.

Figure 2 diagrammatically illustrates a further embodiment of the invention.

20 Figure 3 diagrammatically illustrates a method of determining the desired gas pressure within the bulb of the light source.

As illustrated in Figure 1, the structure 25 comprises a bulb or container —1— formed of glass or other suitable transparent material, altho it would not be essential that the entire wall of the container should be transparent, yet sufficient of the wall should be transparent in order to permit the passage of light rays as desired. This bulb may be 30 of any suitable form, but is shown in the form of a cylinder. However, a sphere or other form would be satisfactory.

The induction coil —2— may, as shown, be wound about or disposed around the bulb 35 —1— and its terminals may be connected to any suitable source of high frequency oscillating current. In Figure 1 there is illustrated a means for producing such a high frequency oscillating current, and this may comprise a circuit which includes a current of suitable voltage at a required frequency, as 40 for instance, sixty (60) cycles.

This current may be stepped up as desired 45 by step-up transformer —3— and led to the discharge gap —4—, a safety gap —5— being provided, if desired. Suitable electrostatic condensers —6— are included in the circuit, safety gaps —7— and —8— being 50 provided, if desired. The leads from the

condensers are connected to the terminals of the induction coil —2—.

It is found that when bulb —1— is filled with an inert gas such as helium, argon, neon, nitrogen, etc., that the passage of a high 55 frequency oscillating current through coil —2— will cause the gas to glow, producing an intense light source. The source of light thus produced may be utilized for any purpose desired, and in Figure 2 there is illustrated a means for varying the produced light in accordance with sound waves. In this case the terminals of the coil —2— are connected to the output of a high frequency audion oscillating system, the structure and arrangement of the parts of which is well known.

The input of this high frequency audion oscillating system may be connected to a microphone —9— by means of which current 70 flowing in the circuit is modulated in accordance with sound waves, with the result that the light waves emanating from the bulb —1— will vary in accordance with the variations of the electrical circuit to which coil —2— is connected, as effected in accordance 75 with sound wave variations.

In order to empirically determine the desired pressure of gas for various cases and for various conditions of operation and sizes of 80 devices, I have illustrated in Figure 3 two bulbs —11— and —12— of similar form, size and shape. The bulb —11— contains no electrodes, but in the bulb —12— there are placed two spaced electrodes —13— and —14— which may be connected to either of the high frequency circuits described.

The gas inlets —15— and —16— of the bulbs —11— and —12— respectively may be connected by conduit —17— to a source of 85 gas supply under pressure. The gas is allowed to enter both bulbs from this single source until such a time as a glow takes place in the bulb —12— between the electrodes —13— and —14—. When the desired character of glow has been reached, the bulb —11— is sealed off the inlet —15— and is then in condition for use in accordance with the disclosure of Figures 1 and 2.

Altho I have shown and described specific 100

structures as constituting embodiments of the invention, I do not desire to restrict myself to any means of producing high frequency oscillating current for supply to the induction coil or to any means for modulating current flowing in such circuit, as various changes and modifications may be made within the scope of the appended claims.

I claim:

- 10 1. A source of light comprising a bulb having a wall permitting the passage of light rays, a gas within the bulb, a coil adjacent the bulb, means for producing high frequency oscillating currents in the coil, and means for modulating said current in accordance with sound wave variations.
- 15 2. A source of light comprising a bulb having a wall permitting the passage of light rays, an inert gas within the bulb, a coil around the bulb, an audion oscillating system connected to said coil for producing high frequency currents in said coil and means for modulating said current in accordance with sound wave variations.
- 20 25 In witness whereof I have hereunto set my hand this 20th day of July 1928.

THEODORE WILLARD CASE.
